UNITED STATES PATENT OFFICE.

WILLIAM H. DUNN, OF CHICAGO, ILLINOIS.

CLEANSING-MACHINE.

No. 851,736.

Specification of Letters Patent.

Patented April 30, 1907.

Application filed March 16, 1906. Serial No. 306,476.

To all whom it may concern:

Be it known that I, WILLIAM H. DUNN, a citizen of the United States of America, residing at No. 2018 West Adams street, in the city of Chicago, county of Cook, and State of Illinois, have invented a new and useful Improvement in a Cleansing-Machine, of which the following is a specification.

My invention relates to the production of a simple and inexpensive cleansing machine and has for its special object the production of such a machine in which the articles to be cleansed may be introduced, cleansed and removed without the necessity of introducing the hands into the cleansing fluid, and in which the cleansing fluid will be thoroughly and effectively circulated through the articles to be cleansed.

To the effectuation of the above objects my invention consists of the new and novel form and combination of parts as will presently appear.

In the drawings:—Figure 1 is a vertical section of the containing tank and circulator assembled. Fig. 2 is a section of the splash-rim. Fig. 3 is a detail of a portion of the circulator. Fig. 4 is an elevation of the receptacle for holding the articles to be cleansed. Fig. 5 is a top plan view of the containing tank and circulator with the cover and splash-rim removed.

The reference numeral 1 designates the containing tank which may be made in any desired form which will permit of the rotation of the circulator to be hereafter described. In the present embodiment of my invention I have given the tank the form of a bucket or pail. At the center of the bottom of the tank is provided the short post 2 extending into the tank and having in its top the depression 3. The tank is further provided with the bail 4 for the purpose of easily lifting it and the cut away portion 5 through which projects the handle 6 for rotating the circulator.

For the purpose of circulating the cleansing fluid I provide the circulator consisting of the hub plate 7 having on its under side the projection 8. Extending radially from the hub plate 7 are the spokes or pieces 9 the outer ends of which are connected with the strengthening hoop 10 and the practically vertical pieces 11. The upper ends of the vertical pieces 11 are connected by means of the hoop 12 and are further re-inforced by

means of the pieces 13 which are practically L shaped in cross-section. To alternate spokes 9 and vertical pieces 11 are attached the plates 14 which project at an angle to the direction of motion when the circulator is rotated. The plates 14 which are attached to the spokes 9 extend at an angle with the bottom of the containing tank 1 while the plates 14 which are attached to the vertical pieces 11 extend at an angle with the sides of said tank. To the hoop 12 is attached the handle 6 by means of which the circulator is rotated or oscillated.

For the purpose of holding the articles to be cleansed I provide the wire or open work receptacle or basket 15 having the bail 16 by which it can be lifted. For preventing the cleansing fluid from being splashed from the tank I provide the splash-rim 17, which consists of the outer wall 18 closely contacting the inside of the containing tank 1, the inner wall 19 which curves upward and extends over the top of the tank 1 after its juncture with the outer wall 18, and the curved bottom wall 20 which connects the bottoms of the walls 18 and 19 and curves over the hoop 12 of the circulator. The cover 21 is further provided for covering the tank 1. This top rests upon the top of the splash-rim.

To operate my machine the circulator is placed in the tank with the projection 8 resting in the depression 3. The basket 15 containing the articles to be cleansed is placed in the circulator. The splash-rim is adjusted, a sufficient amount of cleansing fluid poured into the tank, and the cover or top 21 put in place. The circulator is then oscillated by means of the handle 6 extending through the cut away portion 5. It will be seen that the plates 14 extending at an angle to the direction of rotation create a circulation of the cleansing fluid over, around, about and through the articles to be cleansed.

It is evident, from the foregoing description, taken in connection with the drawings, that I provide a simple, inexpensive and practical cleansing machine.

Having described my invention what I claim as new and desire to secure by Letters Patent is:—

In a cleansing machine, the combination of a containing tank, a circulator rotatably located therein having radial and vertical members provided with plates set at an angle to the walls of the containing tank adjacent

thereto, means for oscillating said circulator extending from the top rim thereof outwardly through an aperture in the upper part of said containing tank, and a containing basket adapted to be placed within said circulator and to be supported and rotated thereby.

In testimony whereof, I have signed my name to this specification in the presence of two subscribing witnesses.

WILLIAM H. DUNN.
